UNITED STATES PATENT OFFICE

2,539,481

TOILET SEAT CONSTRUCTION

David J. Rosenheim, New York, N. Y., assignor
to Lapin Products, Inc., Newark, N. J., a corporation of New York

Application June 3, 1948, Serial No. 30,770

1 Claim. (Cl. 4—237)

1

The present invention relates to a plastic toilet seat construction.

It is among the objects of the present invention to provide a novel, sturdy, durable and attractive toilet seat construction which may be readily molded out of plastic material by injection or other molding procedures, and which will be devoid of crevices or recesses likely to catch dirt and which also may be most readily cleaned.

Another object is to provide a novel, molded, plastic toilet seat and cover construction which will be of light weight and durable material and which will have a relatively simple hinging construction and which will not require added elements either such as rubber stops or covering posts or plates.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

In accomplishing the above objects it has been found most satisfactory, according to one embodiment of the invention, to form the toilet seat and cover as two integral, injection molded pieces of cellulose acetate, styrene, methacrylate resins or other similar resins with appropriate integrally molded cross members or ribs to give suitable strength.

The stop elements instead of being formed of a plastic or rubber material are molded integrally with the body of the cover and the seat and are desirably attached to the reinforcing rib members, which either may extend transversely across the body portions or form the marginal edges of the body portions.

The cover and seat may be sold as one unit and they may be conveniently hinged together by providing upstanding flanges at the sides of the cover and base elements adjacent the rear thereof.

The invention also consists in certain new and original features of construction and combination of parts, hereinafter set forth and claimed and as to its other objects, features and advantages, the mode of operation and manner of its organization, these may be better understood by referring to the following description considered in connection with the accompanying drawings forming a part thereof in which:

Fig. 1 is a side elevational view of a toilet bowl construction showing the side elevational view of the annular base or bottom seat member of the

2

present invention in position thereon upon a relatively reduced scale.

Fig. 2 is a top plan view of the annular base or bottom seat element of the toilet seat construction of the present invention.

Fig. 3 is a bottom plan view of the base or bottom seat element of the toilet seat construction of the present invention.

Fig. 4 is a fragmentary transverse sectional view upon the line 4—4 of Fig. 1 and upon an enlarged scale as compared to Fig. 1.

Fig. 5 is a side elevational view similar to Fig. 1 of the annular base element as well as the cover element of the toilet seat structure, according to the present invention.

Fig. 6 is a top plan view taken upon the line 6—6 of Fig. 5.

Fig. 7 is a bottom plan view of the cover element taken upon the line 7—7 of Fig. 5.

Fig. 8 is a transverse sectional view upon an enlarged scale, taken upon the line 8—8 of Fig. 6.

The cover structure rests upon the bowl B and it is provided with a hinged attachment C to said bowl B. The base section or element A of the toilet seat structure is provided with a stop element D.

Referring to Figs. 5 to 8, there is shown the cover element E which rests upon the annular base A and also has a hinged connection at C to the lower annular element A.

Referring to the lower element A itself, as best shown in Figs. 1 to 4, the upper rim 10 of the bowl B supports the stop elements D, which extend downwardly from the hollow curved section 11. The section 11 has a relatively steep, sharply down-turned outer portion 12 of a relatively shallow, gradually sloping inward portion 13.

The inner and outer curved portions 12 and 13 will terminate at the edges 14 and 15 substantially above the flat surface 16 of the top rim 10 of the bowl B.

The rear of the seat, as indicated in Figs. 1 to 4, has the upstanding flanges 18 which have an opening 17 for receiving the pivot rod 19. The pivot rod 19 has the down-turned ends 20 which are attached at 21 to the rear section 50 of the rim 10 of the bowl B.

The hollow portion 51 is provided with the cross webs or transverse integrally molded elements 22 and 23, which have the short cross or transverse portions 25 and 26. These portions extend below the edges 14 and 15, as shown best in Fig. 4, and form stops against the upper surface 16 of the rim 10.

The projecting crosses 25 and 26, as indicated in Fig. 4, are of such size and length as to afford in themselves satisfactory resilient stops against the top rim 10 of the bowl B. The thickness of elements 22, 23, 25 and 26 is the same or slightly more than the thickness of the sloping portions 12 and 13. These elements 22, 23, 25 and 26 not only give sufficient rigidity to the element A, but also permit sufficient residual flexibility.

The flanges 18 have lower portions 29 which extend below the curved portions 11 and which receive the pivot pin 19. The pivot pin 19 extends through the portions 30, as shown in Fig. 2.

Between the cross members 22 and 23 are provided the strengthening ribs 35 and, if desired, other strengthening ribs similar to 35 might be provided, depending upon the thickness of the shell 11.

The corners between the transverse ribs 22, 23 and 35 are curved, as indicated at 36, 37, 38, 40 and 41, so as to render the seat more sanitary and prevent collection of dirt or grime at these points.

The cover E consists of a flat shell with a base 70 having a down-turned edge 71, which has projecting integral cup 72 contacting the dome of the shell 11. The projections 12 are spaced, as indicated on Fig. 5. The rear of the shell has the extension portion 73 which fits on the pivot pin 74 extending through the side flanges 75 of the rear extension 73. The rear extension 73 has a back flange 76.

It is thus apparent that the present applicant has provided a simply molded, durable, firm, rigid toilet seat shell and cover, which is sanitary and attractive in appearance and which will stand up over long periods of time.

As many changes could be made in the above toilet seat construction and many apparently

widely different embodiments of this invention could be made without departing from the scope of the claim, it is intended that all matter contained in the above description or shown in the accompanying drawings shall be interpreted as illustrative and not in a limiting sense.

Having now particularly ascertained the nature of the invention, and in what manner the same is to be performed, what is claimed is:

10 A toilet seat construction comprising a pivotally mounted integrally molded one piece plastic shell having a relatively steep sharply down-turned outer portion and a gradually sloping inner portion, the edges of said outer and inner portions lying in the same plane, cross-shaped reinforcing members molded integrally with the shell and extending between the outer and inner portions at spaced intervals, the lower edges of the cross-shaped members extending below the lower edges of the outer and inner portions of the shell to form toilet bowl engaging feet for spacing the shell from the upper edge of a toilet bowl.

DAVID J. ROSENHEIM.
